MOLD FILLING MECHANISM FOR GRID PLATE CASTING MACHINES

Arthur D. Lund, Minneapolis, Minn., assignor to
Solar Corporation, Milwaukee, Wis., a corpora-
tion of Delaware

Original application May 17, 1947, Serial No.
748,679. Divided and this application Novem-
ber 5, 1948, Serial No. 58,461

9 Claims. (Cl. 22—79)

1

This invention relates generally to improvements in machines for casting storage battery grid plates and analogous articles, and more particularly to improvements in mechanism for filling the molds of such machines with the molten metal.

This is a division from my prior, co-pending application for Grid Plate Casting Machine, Serial No. 748,679, filed May 17, 1947, and in that application there is disclosed a machine having cooperating, stationary and movable molds with matrix faces for casting the plates. The molds are moved together face to face and in such position are filled or charged with molten metal poured in from the top. After the metal hardens the molds are then separated to drop out the cooled casting and are moved back together for the next charge. The machine is a production unit operating rapidly and continuously to turn out large quantities of plates with but little manual attention and it is obvious that the charging and filling of the molds must fit in with the movements of the molds, i. e., must be properly timed, and the exact amount of metal to properly fill the molds must be poured each time.

It is accordingly the primary object of this invention to provide mold charging or filling mechanism operative in synchronism with the mold travel to deliver or ladle a selected volume of molten metal from a melting pot to the molds. Another object is to provide mold filling mechanism which will permit the precise selection of the volume of metal filled into the molds each time, and which has a novel action such as to deliver the selected volume regardless of the varying level of metal in the melting pot. A further object is to provide mechanism of this nature which will permit the ladles handling the metal to be elevated out of the pot when the machine is shut down so that the ladles will not become frozen in as the metal cools in the pot.

These and other ancillary objects and advantages of the invention will be made apparent in the course of the following specification wherein reference is had to the accompanying drawings, 45 in which:

Fig. 1 is a side view of the casting machine embodying my invention.

Fig. 1a is a detail view of the actuating and timing cams for the molds and filling mechanism.

Fig. 2 is a plan view of the machine of Fig. 1 but with certain parts broken away and omitted.

Fig. 3 is a fragmentary cross sectional view substantially along the line 3—3 in Fig. 1.

2

Fig. 4 is a fragmentary longitudinal section along the line 4—4 in Fig. 3.

Fig. 5 is an enlarged detail end elevation of the actuating and regulating elements of the mold filling mechanism as viewed substantially along the line 5—5 in Fig. 1.

Fig. 6 is a fragmentary sectional view along the line 6—6 in Fig. 7.

Fig. 7 is taken substantially along the line 7—7 in Fig. 5.

Figs. 8, 9 and 10 are all progressive detail views taken substantially along the line 8—8 in Fig. 5.

Fig. 11 is a fragmentary detail sectional view of the upper part of one stationary mold, and 15 adjacent edge of the melting pot, and showing also the ladle and illustrating in dotted lines its dumping action.

Only so much of the casting machine, per se, as will be necessary to the understanding of the mold 20 filling mechanism will be referred to herein, since other details are described at length in my prior application above identified.

Referring now more particularly and by reference characters to the drawing, the machine 25 comprises a main frame designated generally at A adjacent one end of which is supported a melting pot B wherein is contained the molten metal used for the castings. For convenience in description this end of the machine is hereinafter considered as the forward end. The castings are made in cooperating stationary molds C and movable molds D, the former being mounted immediately adjacent the rear edge of the pot B. The molds have matrix surfaces in their meeting faces 30 and when the molds are closed they are filled from the top by mold filling mechanism designated generally at E.

There are two each of the molds C and D so 40 that the machine casts two plates each operation and the movable molds D are carried upon a carriage 18 slidable forwardly and rearwardly upon the frame A in guides 11 secured to upper edges of the spaced sides 12 of the frame (Fig. 3). This carriage is reciprocated by a main ram or fluid 45 motor 13 having a cylinder 14, secured to a cross member 14a joining the sides 12 beneath the carriage, and a rearwardly extending plunger 15 anchored at 16 to a flange 17 depending from the carriage. Fluid is supplied selectively to the opposite ends of the cylinder 14, to extend or retract the plunger 15, through fluid lines 18 and under control of a manually actuable valve 19 mounted on a rear corner of the main frame. The movable molds D are further moved toward 50 and away from the stationary molds by shorter

rams or fluid motors, indicated at 20, having cylinders 21 secured at rear ends to an upstanding web 22 on the rear end of the carriage 16. Plungers 23 extend forwardly from the cylinders 21 and are secured at 24 to mounting heads 25 (one for each mold) which are slideable in guides 26 secured atop the carriage. Fluid is supplied to opposite ends of the cylinders 21 through flexible conduits 27 from a control valve 28 also secured on the side of the machine, forwardly of the valve 19. The movable molds are secured on the forward ends of the heads 25.

This arrangement is obviously such that the entire carriage and mold assembly may be moved through a long stroke by the ram 13 to draw the movable molds well back from the stationary molds for adjusting or smoking the molds as pointed out in my earlier application. This is done at any time by actuating the hand valve 19. The normal, shorter working stroke of the movable molds is, however, accomplished by the rams 20 and under control of the valve 28. This valve 28 is controlled automatically through mechanism including a motor 29 which is mounted on a base 30 carried at the rear end of the machine. The motor drives a speed reducer unit 31 through a belt 32 and driving the belt is a conventional variable speed pulley 33 by which the output speed of the unit 31 may be regulated in a well known manner. The output shaft 34 (Fig. 2) of the unit 31 drives a cam shaft 35 which is journaled in a housing 36 secured to the side of the machine below the valves 19 and 28. As best shown in Fig. 1a there are two cams 37 and 38 mounted on the cam shaft inside the housing 36. The cam 38 is fastened by its hub 39 upon the cam shaft 35 while the cam 37 is loose on the shaft but has arcuate slots 40 in which are positioned bolts 41 carried by cam 38. Thus the two cams rotate with the cam shaft but the angular relationship between the two may be readily adjusted. The cam 37 operates the valve 23 as will now be described, while the cam 38 synchronously operates the mold filling mechanisms E as will later appear, and it is for timing these operations with respect to each other that I provide the said cam angle adjustments.

A short rock shaft 42 is journaled in the cam housing 36 and an arm 43 on the shaft carries a roller 44 riding the cam 37. Externally of the housing a lever 45 is mounted on the shaft 42 (Fig. 1) and a retractile coil spring 46 pulls on this lever to hold the roller 44 on the cam. A short link 47 connects the lever 45 with a rock arm 48 pivoted at its lower end by a shaft 49 journaled in the frame side 12. The upper end of the arm 48 is pivoted at 50 to the rear end of a link rod 51 which extends forwardly to and is pivoted at 52 to an arm 53. While there is a manual override or release for the valve 28, for present purposes it is sufficient to understand that forward and rearward swinging movement of the arm 53 will operate the valve to admit fluid to the opposite ends of the cam cylinders 21 and the arm will, of course, be so moved by the link rod 51 which is moved forwardly and rearwardly by arm 48. The cam 37 controls these movements by its contour and speed and thus the molds may be closed to receive the metal and form the casting, and then opened to dump out the casting, repeatedly and at a selected frequency. The completed castings are carried away by a conveyor system indicated generally at F.

It is believed that the foregoing sufficiently describes the casting machine itself and attention

will now be directed to the mold filling or charging mechanism constituting the present invention.

As best shown in Fig. 4 the stationary molds 5 each have an upwardly flaring mouth 54 to receive the metal, terminating in a sharp parting edge 55 from which there slopes forwardly, and down over the adjacent edge 56 of the melting pot B, a drip return surface 57. To prevent rearward splashing of the metal the movable molds have hoods or guards 58 on their upper edges. There are two filling mechanisms, one for each pair of molds, located on opposite forward sides of the machine and since they are essentially duplicates only one will be described and corresponding parts of each given the same reference characters.

Each filling mechanism comprises a bracket 59 which is mounted on and projects laterally from an end casting 60 which joins the frame sides 12 and supports the stationary molds C. The bracket 59 has transversely spaced ears 61 apertured to receive a non-rotatable shaft 62. From the innermost ear 61 there projects upwardly a fixed lug 63 and an adjustable stop screw 64 is threaded therein.

Oscillatably mounted on the shaft 62 by a long sleeve bearing 65 is the upper part of a parallel-motion operating linkage indicated generally at 66 and which acts as a carrier and includes inner and outer arms 67 and 68 having bearings 69 and 70 on aligned axes parallel with the bearing 65. A shaft 71 is journaled through and between the bearings 69 and 70 and at its inner end this shaft has a fitting 72 in which the cranked supporting arm 73 of a ladle 74 is clamped. The ladle thus travels with the shaft 71.

Spaced ears 75 and 76 are carried by a short sleeve 77 which is rockably mounted on the shaft 71 adjacent the outer bearing ear 70 and pivotally mounted on the pin 78 extending between these ears, eccentric to shaft 71, is the upper end of an actuating rod 79. The lower end of the actuating rod 79 (Fig. 1) is pivoted at 80 to one arm 81 of a bell crank lever 82 which is fixed on a rock shaft 83 journaled transversely through the frame sides 12. The opposite end of the shaft 83 carries a corresponding crank lever for simultaneously actuating the feed mechanism on the opposite side of the machine. The remaining arm 84 of the bell crank lever 82 has pivotally attached thereto at 85 the forward end of a connecting rod 86 and the rear end thereof is pivoted at 87 to a crank lever 88. This lever has a shaft 89 journaled in the housing 36 and internally thereof the shaft carries an arm 90 on the end of which is a roller 91 adapted to ride the periphery of the cam 38. A spring 92 (Fig. 2) is connected between the end of the lever 88 and the frame side 12 at 93 and holds the roller 91 in engagement with the cam 38, as will be apparent.

Supported on the upper, forward part of the frame side 12, below and forwardly of the bracket 59, is an outwardly projecting stub shaft 94 and oscillatably mounted thereon is the lower arm of the aforesaid parallel-motion linkage, designated at 95. This arm 95 is forked at its upper end 96 (Fig. 5) and pivoted in the fork at 97 is the lower end of a parallel-motion link 98. The pivot axis is spaced from the axis of shaft 94 the same distance as the spacing between the axes of the shafts 62 and 71. A projecting ear 99 on the arm 95 serves as the anchor point for the lower end of a retractile coil spring 100 and the upper end of this spring is connected to a short link bar 101.

which is pivotally attached at 102 to the inner ear 76. The spring thus exerts a downward pull on the ears 75 and 76 forward of the axis of the shaft 71 so that the ears and attached sleeve 77 tend to turn clockwise on the shaft at all times. This movement is normally limited by the engagement of a stop surface 103 on the outer ear 75 with an abutment 104 on the arm 63, as seen in Figs. 8 and 9 particularly.

The upper end of the link 90 has integrally formed therewith a bearing sleeve 105 which journals on the shaft 71 inwardly of the sleeve 77 forming the pivot connection completing the parallel-motion linkage on the axes of the elements 61 and 71, and 94 and 97. Also positioned on the shaft 71 and keyed thereto at 106 (Fig. 6) are a pair of spaced sleeves 107 and 108 between which fits the sleeve 105. These sleeves 107 and 108 are connected by and support a stop bar 109 and the sleeve 105 has a tapped projecting lug 110 in which is threaded a screw 111 adapted to bear on this stop bar (Fig. 7). The screw 111 has a knurled knob 112 by which it may be adjusted by hand and has a conventional spring locking or detent mechanism 112a. The stop bar 109 also lies in the path of an abutment or stop surface 113 on the ear 76 (Figs. 9 and 10). A retractile coil spring 114 is stretched between a lug projection 115 on the sleeve 107 (opposite the stop bar 109) and a connection 116 on the lower end of the link 90.

In what may be called a normal or starting position for the feed or filling mechanism the parts assume the positions shown in Figs. 1 and 8, and in such position the ladles 74 are lowered into the melting pot B below the level of the molten metal therein as seen in Fig. 4. The rotation of the cam 33 will now periodically actuate the roller 91 to swing the lever 83 to the left as viewed in Fig. 1, thus exerting a pull upon the connecting rod such as to turn the bell crank lever 82 and attached rock shaft in a counter-clockwise direction. The actuating link 79 will thus be thrust upwardly and from the starting position of the parallel-motion linkage this upward movement of the link will be transmitted through the ears 75 and 76 to the shaft 71 to swing the upper arm part 66 of the linkage in a counter-clockwise direction as will be understood. This movement will continue until the abutment 113 on the ear 76 contacts the stop bar 109 as seen in Fig. 9 at which point the shaft 71 will have been moved upwardly to the uppermost limit of its travel. This movement of the shaft 71 will, of course, swing the ladles 74 upwardly and rearwardly out of the melting pot B to a position over the stationary molds C at which point this travel movement of the ladles will cease. During such movement, however, the ladles have lifted a quantity of molten metal from the melting pot and it will be understood that since this movement of the ladles is controlled by the parallel-motion linkage, it will be accomplished without any tilting action of the ladles such as would cause them to spill any of their contents.

The upward travel of the actuating link 79 continues past the point seen in Fig. 9 and in so doing now swings the ears 75 and 76 about the axis of the shaft 71 to the position shown in Fig. 10. This motion of the ears 75 and 76 is, however, transmitted to the shaft 71 through the engagement of the abutment 113 with the stop bar 109 so that the shaft itself is turned through a part of a turn in a counter-clockwise direction after it has reached the aforesaid upper limit of its

swinging motion. This rotary motion of the shaft 71, through its cranked connection 118 with the fitting 72, then serves to tip the ladle 74 to its dotted line delivery position as shown in Fig. 11 so that the contents of the ladle will be delivered between the molds. Upon the return downward movement of the actuating link 79 the ears 75 and 76 will first turn back in a clockwise direction until the stop bar 109 reaches its normal position against the stop screw 111 under the influence of the spring 114. This will return the ladle 74 to its normal position, seen in full lines in Fig. 11, and a continuation of the downward movement of the link will then pull the shaft 71 and associated parallel-motion linkage back to starting position due to the contact of the stop surface 113 with the abutment 104. This completes the cycle of operation and returns the ladle to the melting pot to gather a new load of molten metal.

The spring 100 serves to normally bias the ears 75 and 76 in a clockwise direction and so maintain the stop surface 113 in contact with the abutment 104 as will be readily understood. The tipping motion, therefore, is carried out against the resistance of the spring 100 in the translation of the parts from the positions Fig. 9 and Fig. 10, and the purpose of the link bar 104 is to allow this further or tipping motion of the ears and attached elements while keeping the line of tension of the spring forwardly of the axis of the shaft 71 so that the ears will be restored to their normal positions and the ladles returned to their normal operating angle. The function of the spring 114 is to bias the stop bar 109 also in a clockwise direction and cause it to follow the motion back to its normal position of Fig. 7 after the ladles have been tipped. It will be apparent that the angle of the ladle 74 may be adjusted by slightly turning the shaft with respect to the parallel-motion linkage and it is for the purpose of making this adjustment that the screw 111 is provided. Obviously as viewed in Fig. 11 if this screw is backed off, the stop bar 109 may be turned slightly in a clockwise direction to change the ladle angle and vice versa. The aforesaid uppermost limit of travel of the shaft 71 with the parallel-motion linkage is set and limited by the stop screw 64 which engages an abutment 119 on the arm 67 as seen in Fig. 7.

Each ladle 74 has a wide cupped or concaved bottom portion 120, the ends of which are closed by the crank connection 73 and by a flange 121 so that as the ladle is lifted from the pot B a quantity of molten metal will be carried upwardly in this cupped bottom. It will be noted that the forward edge 122 of the ladle stands considerably below the rear edge 123 over which the material will spill as it is poured into the mold and thus that it is important that the angle of the ladle does not change as it is lifted from the melting pot. Otherwise, material would spill from this lowermost edge and it is, of course, for this reason that I employ the parallel-motion linkage for controlling the travel of the ladle. Obviously, too, the angle at which the ladle is adjusted by the screw 111 will vary the level of the edge 122 with respect to the edge 123 and so quite precisely control the amount of molten metal which the ladle will hold. The adjustment of the stop screw 64 is made so that the travel of the parallel-motion linkage will lift the ladle to a dumping position at which its edge 123 will just tip over the parting edge 55 of the mold to deliver the molten metal onto the surface 54 which will, of

course, guide it between the molds. Any material which may spill upon the edge 55 will be directed by the surface 51 back to the melting pot as will be readily evident. However, since the axis of the shaft 71 in the dumping position of the parts stands almost exactly aligned with the edge, 123 as indicated at the junction of the lines 126 and 127 in Fig. 11, the tipping or dumping action will cause the ladle edges 123 to turn over just rearwardly of the mold edge 55 so that there is 10 little likelihood of spillage.

It is desirable, when the machine is shut down, to lift the ladles 74 out of the melting pot B so that they will not "freeze" into the cooling metal, and also to be able to lift the ladles into the clear while the rest of the machine runs, in making mold adjustments, etc. For this purpose I provide a cam 139 (Fig. 1) which is mounted on a stub shaft 131 journaled on the frame side 12 below the bell crank lever 82. The shaft may be turned by a handle 132 to run the cam up under a roller 133 on the arm 81 of the bell crank lever and thus urge the rods 79 upwardly and elevate the ladles moving the parts about to the position of Fig. 9. However, the ladles will continue to tilt in these elevated positions and will thus dump their contents, and afterward remain empty until they are returned to the melting pot, by again turning the handle 132.

From the foregoing it will be seen that I have provided a mold filling mechanism which will accurately and positively ladle preselected and readily controlled charges of the molten metal into the molds, in proper turned relation to the opening and closing of the molds, all as necessary to accommodate the mold charging operation to the production characteristics of the machine as a whole.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a grid plate casting machine, mechanism for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle.

2. In a grid plate casting machine, mechanism for filling casting molds from an adjacent molten metal container comprising a horizontal support located on the frame of the casting machine at one side of the molds and the container, arms each journaled at one end on said support, a ladle shaft journaled in bearings on the ends of the arms re-

5 mote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, and a spring connected to the ears eccentrically of said ladle shaft to hold said stop surface in contact with the arm whereby the ears and arms will swing as a unit until the abutment engages the stop member.

3. In a grid plate casting machine, mechanism 15 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 20 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, a spring connected to the ears eccentrically of said ladle shaft to hold said stop surface in contact with the arm whereby the ears and arms will swing as a unit until the abutment engages the stop member, and a second spring connected to the stop member to bias the ladle shaft toward a position for leveling the ladle.

4. In a grid plate casting machine, mechanism 25 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 30 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle.

5. In a grid plate casting machine, mechanism 35 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 40 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, a spring connected to the ears eccentrically of said ladle shaft to hold said stop surface in contact with the arm whereby the ears and arms will swing as a unit until the abutment engages the stop member, and a second spring connected to the stop member to bias the ladle shaft toward a position for leveling the ladle.

6. In a grid plate casting machine, mechanism 45 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 50 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, a spring connected to the ears eccentrically of said ladle shaft to hold said stop surface in contact with the arm whereby the ears and arms will swing as a unit until the abutment engages the stop member, and a second spring connected to the stop member to bias the ladle shaft toward a position for leveling the ladle.

7. In a grid plate casting machine, mechanism 55 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 60 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, a spring connected to the ears eccentrically of said ladle shaft to hold said stop surface in contact with the arm whereby the ears and arms will swing as a unit until the abutment engages the stop member, and a second spring connected to the stop member to bias the ladle shaft toward a position for leveling the ladle.

8. In a grid plate casting machine, mechanism 65 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 70 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, a spring connected to the ears eccentrically of said ladle shaft to hold said stop surface in contact with the arm whereby the ears and arms will swing as a unit until the abutment engages the stop member, and a second spring connected to the stop member to bias the ladle shaft toward a position for leveling the ladle.

9. In a grid plate casting machine, mechanism 75 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 80 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, a spring connected to the ears eccentrically of said ladle shaft to hold said stop surface in contact with the arm whereby the ears and arms will swing as a unit until the abutment engages the stop member, and a second spring connected to the stop member to bias the ladle shaft toward a position for leveling the ladle.

10. In a grid plate casting machine, mechanism 85 for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member 90 fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, the other ear having a stop surface for engaging a part of one of the arms carrying the ladle shaft, a spring connected to the ears eccentrically of said ladle shaft to hold said stop surface in contact with the arm whereby the ears and arms will swing as a unit until the abutment engages the stop member, and a second spring connected to the stop member to bias the ladle shaft toward a position for leveling the ladle.

member, whereby when the rod has raised the ladle to a position over the mold said abutment contacts said stop member and dumps the ladle, a second support located on the frame of the casting machine below the first mentioned support, an arm journaled at one end on said second support, and a link connected to the end of the last mentioned arm remote from the second support and to the ladle shaft to control the ladle angle as it is moved upwardly by said actuating rod.

5. In a grid plate casting machine, mechanism for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, an adjusting screw for engaging the said stop member, and means rotatably mounted on the ladle shaft supporting the screw for adjustment with reference to the stop member and thereby adjusting the ladle shaft in its bearings on the arms.

6. In a grid plate casting machine, mechanism for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, a second support located on the frame of the casting machine below the first mentioned support, an arm journaled at one end on said second support, a link connected at its lower end to the end of the last mentioned arm remote from said second support, a sleeve on the upper end of the link journaled on the ladle shaft, and an adjusting screw carried by said sleeve for engagement with the said stop member to turn the ladle shaft in its bearings and regulate the ladle angle.

7. In a grid plate casting machine, mechanism for filling casting molds from an adjacent

molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, a lug member on the support, and a screw in said lug member adjustably positioned in the path of one of said arms to limit the upward motion of the ladle toward its dumping position.

15 8. In a grid plate casting machine, mechanism for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, a lug member on the support, and a screw in said lug member adjustably positioned in the path of one of said arms to limit the upward motion of the ladle toward its dumping position.

20 9. In a grid plate casting machine, mechanism for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, a lug member on the support, and a screw in said lug member adjustably positioned in the path of one of said arms to limit the upward motion of the ladle toward its dumping position.

25 10. In a grid plate casting machine, mechanism for filling casting molds from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, a power-operated linkage for operating the actuating rod and manually operated means pivoted on said frame for elevating the actuating rod independently of said power-operated linkage so that the ladles may be held in a raised position out of the molden metal container.

30 11. In a grid plate casting machine, mechanism for filling casting molds, each comprising a stationary section and a movable section, from an adjacent molten metal container comprising a horizontal support located on the frame of the casting machine at one side of the molds and the container, arms each journaled at one end on said support, a ladle shaft journaled in bearings on the ends of the arms remote from the support, a ladle fixed to said ladle shaft, a pair of ears rotatably mounted on said ladle shaft, a single upwardly and downwardly movable actuating rod pivotally attached at its upper end to each of said ears at a point eccentric to said ladle shaft and operative as it moves upwardly to swing the ears, ladle shaft, ladle and arms about the axis of the journals of the arms on the support, a stop member fixed to the ladle shaft and an abutment on one of the ears eccentric to the ladle shaft, said abutment being so located that as the arms rise from the horizontal the abutment approaches the stop member, whereby when the rod has raised the ladle to a position over the mold said abutment contacts said stop member and dumps the ladle, a power-operated linkage for operating the actuating rod and manually operated means pivoted on said frame for elevating the actuating rod independently of said power-operated linkage so that the ladles may be held in a raised position out of the molden metal container.

that as the arms rise from the horizontal the abutment approaches the stop member, whereby when the rod has raised the ladle to a position over the mold said abutment contacts said stop member and dumps the ladle, each of said stationary mold sections being mounted on a part of the frame immediately adjacent the molten metal container and having a projection on its rear face overhanging an upper edge of said molten metal container and each of said stationary mold sections having at its top a knife edge with steeply sloping sides so that molten metal spilled on a stationary mold section will not remain thereon but will flow either into the mold cavity or back into the molten metal container. 15
